UNITED STATES PATENT OFFICE.

FRANCIS W. DRAPER, OF RICHMOND, INDIANA. ASSIGNOR TO STARR PIANO COMPANY,
OF RICHMOND, INDIANA, A CORPORATION OF INDIANA.

SILENT-TRAVEL ATTACHMENT FOR PLAYER-PIANOS.

1,112,983.

Specification of Letters Patent.

Application filed July 31, 1913. Serial No. 782,362.

Patented Oct. 6, 1914.

To all whom it may concern:

Be it known that I, FRANCIS W. DRAPER, a citizen of the United States, residing at Richmond, in the county of Wayne and State of Indiana, have invented certain new and useful Improvements in Silent-Travel Attachments for Player-Pianos; and I do hereby declare the following to be a full, clear, and exact description of the invention, such as will enable others skilled in the art to which it appertains to make and use the same.

This invention relates to player pianos and has for an object to provide a silent travel mechanism whereby a certain portion of the music sheet may be passed with accelerated speed over the tracker bar without actuating the action in the usual manner.

It is well known that in the playing of perforated music it is desirable at times to omit the playing of certain parts. It is also desirable that the omission of playing certain parts occupy as short a space of time as possible. The present invention, therefore, is directed to a manually operated device which simultaneously interrupts the action and accelerates the motor, such accelerated speed and interrupted action being also controlled automatically by the rewind mechanism.

A further object of the invention is to provide improved pneumatic means for carrying into effect the general objects of the invention.

With these and other objects in view the invention comprises certain novel constructions, combinations and arrangement of parts as will be hereinafter more fully described and claimed.

In the drawings: Figure 1 is a conventional view of a player piano with the front removed showing the arrangement of the parts. Fig. 2 is a longitudinal sectional view through the motor accelerating pneumatic, taken on the line 2—2 of Figs. 4 and 6. Fig. 3 is a transverse sectional view through the motor accelerating pneumatic taken on lines 3—3 of Figs. 2, 4 and 5. Fig. 4 is a top plan view of the motor accelerating pneumatic with the outer sheet of the casing removed as indicated by line 4—4 of Fig. 2. Fig. 5 is an inverted plan view of the motor accelerating pneumatic with the cover member of the pneumatic removed as viewed from the arrow 5 of Figs. 2 and

3. Fig. 6 is a transverse sectional view through the pneumatic taken on line 6—6 of Figs. 2 and 4. Fig. 7 is a longitudinal sectional view through the action interrupting pneumatic. Fig. 8 is a diagrammatic view of the manual valve and connections. Fig. 9 is a sectional view of the manual valve. Fig. 10 is a sectional view of the junction and valve block.

Like characters of reference designate corresponding parts throughout the several views.

There is shown at Fig. 1 a pneumatic interrupter whose housing 15 is attached to a player piano in position to be subjected to the exhaust of the bellows B preferably by being connected directly to the front or stationary side of the bellows, communication being had through the opening 16, as shown at Fig. 7. The housing 15 communicates through an L 17 with a hose pipe or conduit connected with the action so that the action windchest is exhausted in the usual manner except that the housing 15 is inserted in the run of tubing. Within the housing 15 a valve 18 is located carried upon a valve stem 19 and actuated by a pneumatic 20 so that when the pneumatic 20 is expanded the valve 18 is lifted to close the inner end of the passage to the action windchest and interrupt the movement of the action. To control such pneumatic a tube 21 is provided communicating with an orifice 22 under the pneumatic 20 so that atmospheric air may be introduced within the pneumatic 20 which being subjected to exhaust from the bellows would be raised by the internal air. A bleeder 23 is provided so that under ordinary conditions the spring 24 may hold the pneumatic 20 in collapsed condition and the passage to the L 17 open to permit the action windchest (not shown) to be maintained under exhaust. With the parts shown as at Fig. 7 which is the normal condition, it is apparent that the passage from the action windchest to the bellows is uninterrupted but that when air is admitted through the tube 21 into the pneumatic 20 such pneumatic will be expanded and the valve 18 closed. To admit air to such tube 21 a junction block 25 is provided with which the tube 21 communicates and which is provided with a valve 26 opened by the lever 27 manually, such lever 27 being the lever controlling the

rewind and operated only when the sheet is being rewound. Communicating also with the junction block 25 is a tube 28 which communicates with a manual valve 29. The valve 29 comprises a push button 30 and an inlet valve 31 which closes communication between the pipe 28 and the atmosphere. Such manual valve does not specifically form any part of the present invention.

It is obvious that when the push button 30 is depressed the valve 31 will open communication from the atmosphere to the tube 28, admitting air through junction block 25 to the tube 21 and to the pneumatic 20 whereby such pneumatic will be expanded and the valve 18 closed. Therefore, at any point where it is desired to stop the action the simple depressing of the push button 30 will accomplish the purpose. As it is desirable to move the music sheet as rapidly as possible during such silent travel so that such silent interval will be as short as possible, means is provided for increasing the capacity of the conduit leading to the motor 25 and thereby accelerating the action of such motor simultaneously with closing the valve 18. Such means comprises a branch tube 32 extending also from the junction block 25 and supplied with air simultaneously with the supply of air to the tube 21. The tube 32 leads to the motor accelerating pneumatic 33 which is connected in any manner with an exhaust chamber as for instance through the medium of the tube or conduit 34 directly with the stationary side of the bellows, the same as the interrupter housing 15. The tube 32 leads directly to a pneumatic 35 which is located within a chamber 36 communicating through a passage 37 with the tube 34 and, therefore, subject to exhaust. The admission of air, therefore, to the pneumatic 35 tends to expand the said pneumatic. The pneumatic 35 carries a valve stem 38 which in turn carries a valve 39, such valve 39 being held normally yieldingly closed by a spring 40 and in such closed condition closing communication between the chamber 36 and an adjacent chamber 41. The chamber 41 communicates through passage 42 directly with the fitting 43 which leads to the motor pneumatics, so it will be apparent that when the valve 39 is raised direct communication is established between the exhausted chamber 36 and the motor pneumatic. With the valve 39 closed, the passage for the air through the fitting 43 from the motor pneumatic is first into the chamber 41 and then through an opening 44 controlled by the manual tempo slide 45, through the passage 46 into the pneumatic chamber 47, through the orifice 48 of the block 49 and into the passage 37, as shown particularly at Fig. 3, the passage through the orifice 48 being controlled by a pivoted valve 50 actuated by the movable wall 51 of the pneumatic. The movable wall 51 is connected through a link 52 with such pivoted valve 50 so that as such wall 51 closes the orifice 48 is partially closed. A spring 53 is also provided which tends to hold the movable wall yieldingly open. This pivoted valve with its operating movable wall forms no specific part of the present invention except in combination with the other parts hereinbefore described, such parts being a known automatic tempo control. The exhaust acts first upon the movable wall 51 and if excessive tends to cause the movable wall 51 to close against the tension of the spring 53 which closes the passage 48 thereby subjecting the motor to a substantially constant degree of rarefaction. It will, therefore, be seen that the member indicated as a whole at 33 serves the purpose of automatic tempo control, a manual tempo control, and a means for accelerating the motor automatically when the passage to the action is interrupted as hereinbefore described.

I claim:

1. In a player piano, the combination with a bellows, a conduit leading thence to the action, a pneumatically controlled interrupter in this conduit, a second conduit leading from the bellows to the motor, and pneumatically controlled means in this conduit for increasing its carrying capacity; of a junction block having a four-way passage, tubes leading from two of the arms of said passage to the interrupter and to said means respectively, a valve in the third arm, means for actuating this valve by the movement of the rewind mechanism, a normally closed inlet valve to the fourth arm, and a manual for opening this valve.
2. In a player piano, the combination with a bellows, a conduit leading thence to the action, a pneumatically controlled interrupter in this conduit, a second conduit leading from the bellows to the motor, and pneumatically controlled means in this conduit for increasing its carrying capacity; of a junction block having a four-way passage, tubes leading from two of the arms of said passage to the interrupter and to said means respectively, a valve normally closing the third arm, connections between the rewind mechanism and this valve for opening it when the mechanism is actuated, and a manually operable valve normally closing the fourth arm.

In testimony whereof I affix my signature in presence of two witnesses.

FRANCIS W. DRAPER.
